UNITED STATES PATENT OFFICE.

JAMES LEONARD LAMB, OF WOODBURN, IOWA.

BINDING AND TYING MECHANISM.

1,135,298.

Specification of Letters Patent.

Patented Apr. 13, 1915.

Application filed September 7, 1912. Serial No. 719,143.

To all whom it may concern:

Be it known that I, JAMES LEONARD LAMB, a citizen of the United States, residing in Woodburn, in the county of Clarke and State of Iowa, have invented certain new and useful Improvements in Binding and Tying Mechanisms, of which the following is a specification.

My invention relates to improvements in binding and tying mechanisms, and particularly to that class of machines in which hay bales or similar bundles are bound together and tied.

The object of my invention is to provide a device of this class of simple, durable and efficient construction.

A further object of my invention is to provide a device of this class with means whereby the binding and threading mechanism is operated by means of a plunger.

A further object of my invention is to provide a device of this class with a head block provided with pins by means of which the binding and tying mechanism is set in motion.

A further object of my invention is to provide a device of this class with means for automatically connecting and disconnecting the binding and tying mechanism to and from the plunger.

A further object of my invention is to provide a device of this class whereby the needles are driven simultaneously across the frame from opposite sides.

A further object of my invention is to provide a device of this class provided with a frame so designed as to have a vertical and longitudinal movement with respect to the baling chamber when mounted thereon.

A further object of my invention is to provide a device of this class provided with binding and threading needles designed to be driven simultaneously across the baling chamber on opposite sides of a head block.

A further object of my invention is to provide a device of this class so designed as to be easily and readily applied to a baling chamber of the ordinary construction.

The above and other features, advantages and capabilities of my device will become apparent from a detailed description of the accompanying drawings, in which—

Figure 1 is an elevation of a portion of the baling chamber showing my invention mounted thereon; Fig. 2 is a portion of the baling chamber showing my invention

mounted thereon, showing the side opposite to that shown in Fig. 1; Fig. 3 is a transverse sectional view taken substantially on the line 3—3 of Fig. 2, and looking in the direction indicated by the arrows; Fig. 4 shows a plan view of a portion of the baling chamber with my invention applied thereto; Fig. 5 shows a longitudinal sectional view taken substantially on the line 5—5 of Fig. 1; Fig. 6 is an enlarged detail view partly in section showing the tying mechanism; Fig. 7 is a detail sectional view of a portion of the same taken on the line 7—7 of Fig. 6. Fig. 8 is an enlarged detail view of the ratchet and gear wheel shown in Figs. 1 and 5 which large gear wheel is designed to engage the gear wheel shown in Fig. 6. Fig. 9 is a detail view showing the end of the head block and the dogs which are engaged by the pins on the head block for setting said mechanism in operation; Fig. 10 is a detail plan view of the means for producing the slack in the binding wires; Fig. 11 is a detailed elevational view of the same; Fig. 12 is an enlarged detail view of the end of one of the needles showing the binding wire looped thereover; Fig. 13 is an enlarged detail view of the means for clamping the binding wire in place on one side of the baler; Fig. 14 is an enlarged detail view of the means for clamping the wire on the opposite side of the baler and the means for cutting the wire; Fig. 14^a is an elevation of the same showing the means for holding one of the clamps in closed position until released by the twister; Fig. 15 is an enlarged detail view showing one of the needles engaging the wire; Fig. 16 is a plan view of the head block showing a modified form of the pins mounted therein; Fig. 17 is an elevational view of a portion of the tying mechanism, showing the ends of the jaws in cross section, the jaws being shown in open position and the wires and needles therein preparatory to clamping. Figs. 18, 19, 20 and 21 are diagrammatical views showing the different positions of the binding wire as the bale is formed showing the 1st, 2nd, 3rd, and 4th position respectively. Fig. 22 is a perspective view of the mechanism for tripping the dogs for releasing the head block.

Generally stated my invention consists of a frame adapted to be mounted on the ordinary baling chamber, which frame is provided with springs on its upper side, which

springs rest on the upper side of the baling chamber to permit of vertical movement of said frame and coil springs attached to the upper side of said frame at one end and to 5 the side of the baling chamber at the opposite end to permit of longitudinal movement of said frame, thus giving to said frame a vertical and longitudinal movement. The frame proper consists of a telescoping frame 10 and has mounted on either side a pair of needles so designed that when the frame is drawn outwardly by means of the plunger, the needles will be driven across the frame one pair on each side of a head block. One 15 pair carries the wires across for the new bale and may be termed the threading needles, while the other pair carries the wires across the baling chamber from the opposite side into the tying mechanism for completing the 20 old bale and may be termed the binding needles. The head block is provided with pins designed to engage dogs pivotally mounted on said frame by means of which the frame is set in motion and causes an 25 automatic means to connect with the plunger by means of which plunger the telescoping frame is pulled outwardly, drawing the needles across the frame and carrying the wire therewith as explained. After the 30 frame has been pulled outwardly a predetermined distance the means connecting with the plunger is automatically disengaged and the frame is drawn inwardly by means of a spring which causes the tying mechanism to 35 operate, thus tying the ends of the wires and completing the bale.

Referring to the drawings in detail, I have used the reference numeral 10 to designate the baling chamber as a whole, which 40 may be of any of the ordinary construction, and 11 designates the main frame of the baling and tying mechanism which main frame is provided at its top and bottom with a telescoping frame but as the top and bottom 45 are the same, a description of the top which is clearly shown in Fig. 4 will be sufficient for both. Pivotally mounted on the top of the frame 11 substantially at its center are a pair of arms 12 which arms are pivotally 50 connected at their outer ends by means of a pair of short diverging links 13. Pivotally connected to the arms 12 are a second pair of links 14 which links are pivotally connected at their outer ends to an auxiliary frame 55 15 which auxiliary frame extends entirely around the baling chamber. Mounted on the under side of the upper side of the frame 11 are a pair of steel springs 16 to permit of a vertical movement of the frame 11. 60 On the top and on the bottom of the baling chamber are suitable coil springs 17, which are connected at one end to the frame 15, and at their opposite ends to the main frame 11, for the purpose presently to be 65 described.

18 designates a chute through which the hay is fed into the baling chamber.

19 designates the head block which is provided with pins 20 which pins are designed to travel in the grooves 21 in the baling 70 chamber but where it is desired to use my invention with a baling chamber of the usual construction, that is, one without the grooves, I provide the head block 19 with spring pins as best shown in Fig. 16. The head block is 75 inserted in its place. The hay is then fed into the chamber through the chute which forces the head block longitudinally of the frame, the pins on the head block traveling in the grooves 21. After the head block has 80 thus been moved longitudinally in the baling chamber sufficiently, the pins engage the dogs 23 for a purpose presently to be described. The dogs 23 are arranged in pairs, two on each side one above the other and are 85 pivotally connected to the frame 11 by any suitable means such as the pin shown, the upper dog being connected to the lower one by means of a link 23^a as best shown in Fig. 9. At a point spaced apart from the connection to said frame, said lower dogs are pivotally connected by means of a link 24 to one end of the link 24^b. The said link 24^b is provided at its opposite end with a curved bearing shoulder, which end is pivotally connected to a suitable bracket 24^a. Said bracket is rigidly secured to the main frame 11 by any suitable means. Pivotally connected to the bracket 24^a and the link 24^b is 90 an arm 24^c which arm is provided at its upper end with a lug having a curved bearing shoulder designed to engage the curved bearing shoulder on the link 24^b, by means of which the links 24 and 24^b are forced into the position shown in dotted lines in Fig. 9 95 when the arm 24^c is forced forwardly. The lower end of the arm 24^c is bifurcated and is adapted to be engaged by the lug 26 on the rod 27. The links 24 and 24^b are provided with shoulders 24^c designed to engage 100 each other to prevent said links from being folded in but one direction, thus preventing the dogs 23 from being tripped until said links are forced into the position shown in dotted lines in Fig. 9. 110

We will call the end on which the chute 18 is mounted through which the hay is fed the rearward end and the opposite end the forward end as best shown in Fig. 2. As the head block reaches the main frame 11 and 120 the pins engage the dogs 23 the entire frame 11 is moved forwardly a short distance which allows the pivotally mounted dogs 32 on each side of the auxiliary frame 15 to engage suitable notches in the plunger 30. 125 When the frame 15 is in the position shown in Figs. 2 and 4, the dogs 32 are held out of engagement with the plunger 30 by means of the lugs 33 on the arms 34, which arms are rigidly secured to the sides of the main 130

frame 11 by any suitable means. When the dogs 23 are engaged by the pins on the head block the main frame 11 is forced forwardly a short distance which causes the 5 lugs 33 on the rods 34 to disengage the lugs 32 thus allowing said dogs to be forced into engagement (through a longitudinal opening in the sides of the baling chamber) with the notches in the plunger by means of coil 10 springs 35. It will of course be understood that the plunger has a reciprocatory movement and as it starts on its outward stroke it engages the dogs 32 (that is assuming of course that they have been released as before stated), thus drawing the auxiliary 15 frame 15 outwardly for a purpose presently to be described. After the tying and binding operation is completed and the dogs 23 released the main frame 11 returns to its 20 normal position by means of the compression springs 28 which springs are wound on the rods 28^a. The said rods are rigidly secured at one end to the side of the main frame 11 and slidably mounted at the opposite end in the brackets 29, the latter end being provided with a nut to limit the rearward movement of the frame 11. The brackets 29 are rigidly secured to the side of the baling chamber one on each side by any 25 suitable means. The head block is held in its proper position until after the needles (presently to be described) are driven across the baling chamber and back to their normal position. This is accomplished by means of the links 24 and 24^b and the arm 24^c heretofore described. After the binding and 30 tying operation is completed it is necessary that the dogs 23 be tripped, thus releasing the head block and allowing the frame 11 to be returned to its normal position by means of the springs 28 above described. This I 35 accomplish by means of the rods 27 which are rigidly secured to the auxiliary frame 15 on each side near the lower edge thereof, which rods extend forwardly past the main frame 11 and are provided with a lug 26, but as the construction and operation of each 40 are the same, a description of the operation of one will be sufficient for both. As the auxiliary frame 11 is drawn forwardly by means of the mechanism heretofore described, the lug 26 on the rod 27 forces the arm 24^c into the position shown in dotted lines in Fig. 9, while the links 24 and 24^b are 45 in the position shown in heavy lines in the same figure. The lug 26 is positioned on the rod 27 so that it will slide past the bifurcated end of the arm 24^c, thus allowing said arm to return to the position shown in 50 heavy lines in Fig. 9. After the lug 26 has passed the arm 24^c, said arm swings into a position shown in heavy lines, Fig. 9, where it will be engaged by said lug on its return. The lug 26 is positioned on the rod 27 so 55 that said lug will engage the arm 24^c just before the auxiliary frame 15 has reached its backward limit of movement, at which time the needles have been withdrawn and returned to their normal position. The lug 26 then engages the arm 24^c and by means of 60 the shoulders on said arm and the link 24^b, the links 24^b and 24 are forced into the position shown in dotted lines in Fig. 22, thus tripping the dogs 23 and releasing the head block. The head block is then forced 65 through the baling chamber past the dogs 23 by means of the action of the plunger on the hay within the chamber. As soon as the head block is completely past the dogs 23 the steel spring 24^d on the links 24 and 24^b 70 return said links to their normal position, thus returning the dogs 23 to their normal position at which position they are again engaged by the next head block, for again starting the mechanism in operation. The 75 arm 24^c is so arranged that it will slide past the lug 26 before said lug has reached its backward limit of movement and then swings into the position shown in heavy lines in Fig. 9 whereby the same operation may again be 80 repeated. After the plunger has traveled outwardly a certain distance the dogs 32 are automatically disengaged from the plunger by means of the rollers 36 on the end of the arms 34 which arms are rigidly secured 85 to the frame 11 as best shown in Fig. 5, and the auxiliary frame 15 is then returned to its normal position by means of the said springs 17 one of said springs being positioned on the top of the main frame and the 90 other on the bottom of said main frame, one end of each of said springs being secured to the main frame in any suitable manner and the opposite end connected to said auxiliary frame. During this outward travel of said 95 plunger and before the dogs are released by means of the rollers 36, the threading and binding operation is performed, and during the inward travel of said auxiliary frame by means of the springs 17 as above described 100 the needles are returned to their normal position, the tying operation completed, the dogs tripped and the head block released. 105 The mechanism by which the threading and binding operation is performed, I will 110 now described.

There are two pairs of needles, one pair on each side of the frame which needles are pivotally connected at their outer ends to the links 13 as best shown in Fig. 5 and are 115 provided at their inner ends with a suitable groove for holding a looped wire as best shown in Fig. 12. As the operation of both needles in each pair is the same, a description of the operation of one needle in each 120 pair will be sufficient for both. Referring to Fig. 5 and applying the same designation to the forward and rearward ends of the baling chamber as in Fig. 2 I will designate 125 the pair of needles which are on the forward 130

side of the head block, the binding needles, while that pair on the rearward side of the head block, I will designate as the threading needles. With this understanding as to terms, 37 designates the binding needles and 38 the threading needles.

It may be assumed that the machine is in condition for operation, spools of wire 39 having been arranged on one side of the machine as shown in Fig. 1 and the end of the wire in each case passed forwardly over the rollers 40 and across the baling chamber to the clamp 58 as best shown in Fig. 5, and assuming that a sufficient quantity of hay has been placed in the baling chamber and the head block then placed therein, the wire would then be in the position shown in Fig. 18. The plunger having a reciprocatory movement forces the hay ahead of the head block and the head block through the baling chamber and by means of the hay ahead of the head block the wire is forced into the position shown in Fig. 19. After the wires reach this position it is necessary that sufficient slack be drawn into the wire as shown in Fig. 20, so as to provide an end of sufficient length to reach back across the baling chamber and form a tie as shown in Fig. 21. This is accomplished by the means now to be described.

Secured to one side of the frame 11 are brackets 42 on which is slidably mounted a vertical shaft 43 on which shaft is secured upper and lower arms 44 which arms are provided with upwardly extending ends designed to engage the wire 41. Said shaft is provided at its upper end with a short arm 45 (as best shown in Fig. 10) designed to rest on the bar 46 which bar is slidably mounted on the side of the frame 11 near one end and is slidably connected at its opposite end to a short arm 47. The arm 47 is pivotally mounted near its upper end on the baling chamber 10. The bar 48 is slidably mounted near one end on the frame 11 and is provided at its opposite end with an upwardly bent portion to which is pivotally connected the upper end of the arm 48^b. The arm 48^b is pivotally mounted on the baling chamber 10 by any suitable means as the bolt shown in Fig. 2. The bar 48 is also provided with a notched portion to form a shoulder 48^a for a purpose presently to be described. The bar 46 is provided with a cam portion 46^a which is designed to engage the arm 45 and to raise the shaft 43 when said bar is slid forwardly by means of the head block engaging the lower end of the arm 47. When the shaft is thus raised the arms 44 are necessarily raised upwardly and engage the wire 41. After the operation described above is completed the head block engages the lower end of the arms 48^b by means of which the bar 48 is moved backwardly, thus causing the shoulder 48^a

on the bar 48 to engage the arm 45 thus partly rotating the shaft 43 and throwing the arms 44 out to the position shown in heavy lines in Fig. 10 by means of which the wire is drawn out of position as shown in Fig. 20, thus providing sufficient slack for extending the end of the wire across the baler and tying in the form shown in Fig. 21.

Pivotaly mounted on the side of the frame 11 is a dog 50 (Fig. 11) which is designed to engage the notch in the bar 46 to prevent said bar from sliding backwardly until the proper time. Immediately following the engagement of the dogs 23 by the head block 19 which moves the frame rearwardly a short distance as before described, the lugs 33 on the rod 34 are caused to release the dogs 32 allowing them to engage the plunger 30 by means of which the auxiliary frame 15 is drawn outwardly causing the needles and the arm 52 to travel across the baling chamber. However, it is timed so that just as the arm 52 is moved inwardly the dog 53 engages the pin 53^a on the arm 54 (Fig. 4) and pulls the bell crank lever 55 inwardly. By means of the rod 54^a which rod connects the arm 54 with the bell crank lever 55^a (Figs. 3 and 4) the link 57 which is pivotally connected to the fulcrumed levers 57^a is drawn upwardly thus opening the clamps 58 (presently to be described) and releasing the wire therefrom. At the same time the lug 59 is forced downwardly by which the dog 50 (Figs. 3 and 11) is released allowing the bar 46 to return to its normal position by means of the spring 60, thus returning the arms 44 to their normal position by means of the spring 60^a on the shaft 43. This operation is completed just as the binding needles engage the wire. To hold the wire away from the arms 44 when the shaft is returned to its normal position, I provide the stationary spring arms 61 which are rigidly secured at one end to the side of the main frame 11 by any suitable means such as the bolts shown (Fig. 2) and are provided at their free or opposite ends with a flat surface on which the wire rests. Just preceding the release- 110
ment of the wires from the clamps the movement of the needles 37 are timed so that the ends of the needles 37 strike the wire and carry it across to the twister, (presently to be described). The end of the needle being grooved, and the movement of the needles 37 being timed to strike the wire before it is fully released from the clamps 58, a loop is formed in the wire which will prevent it from slipping over the ends of the needles as it is carried across to the twister. As the needles 37 are traveling across the baling chamber it is necessary that the clamps 58 remain open until the needles 38 carry the end of the wire leading 115
120
125
130

from the spool to the clamps 58. For holding the clamps 58 open until this time, I provide a dog 61^a which is pivotally mounted on the top of the frame 11 and is provided with an outwardly extending arm 62 as best shown in Fig. 4. It will be seen from this that when the clamps 58 are open for releasing the wire by means of the operation heretofore described, the lug 63 will be moved rearwardly sufficiently to engage the upper end of the bell crank lever 55^a by means of which the clamps 58 are held in their open position and in which position they remain until the end of the bar 52 travels across the baling chamber and engages the extending lug 62 on the dog 61^a by means of which the dog is forced out of engagement with the bell crank 55^a, thus allowing the clamps 58 to close. It will of course be understood that the mechanism is timed to be released and the clamps closed at the time the end of the needle reaches said clamps so that the end of the wires may be clamped in place. The needles 38 start across the baling chamber simultaneously with the needles 37 and it is therefore necessary that just as the needles 38 engage the wire that the wire be cut and held on both sides of the place where cut. The end cut away (that is the wire going around the bale) is clamped in place and so held until the needles 37 carry the opposite end of the wire going around the bale across the baling chamber where the two ends are twisted, while the other end (that is the end leading from the spool) is clamped and held until the end of the needles 38 engage it and forces it out of the clamp. For accomplishing this I provide the arm 54 with a bifurcated end as best shown in Fig. 4, in which bifurcated end is designed to travel a bell crank lever 55 as best shown in Figs. 3 and 4, and when the bifurcated end of the arm 54 is moved inwardly by means of the arm 52 the wire is clamped in place and cut by the means now to be described.

Rigidly secured to the side of the frame 11 near the upper edge thereof is an outwardly extending bracket 84 and pivotally mounted on the outer end of said bracket is the outwardly extending arm of the bell crank lever 55 as best shown in Fig. 3. Pivotally connected to the bell crank lever 55 is a downwardly extending link 85 which link is pivotally connected to the fulcrumed blades 86 as best shown in Fig. 3. As the construction and operation of both blades are the same a description of one will be sufficient for both. The said blades are fulcrumed to the side of the frame 11 by means of a suitable pin as best shown in Fig. 14 and are provided with a beveled or sharpened edge as best shown in Fig. 14^a. When the upper end of the bell crank lever 55 is moved inwardly by means of

the bifurcated arm 54 the link 85 is moved downwardly, thus forcing the inner or sharpened ends of the blades 86 upwardly by means of which the wire is cut. Securely mounted on the side of the frame 11 are two clamping devices which are positioned in a line with the path taken by the wires 41 so as to engage the said wires when operated as best shown in Fig. 14^a. As the construction and operation of both of these clamping mechanisms are the same a description of one will be sufficient for both. These may be termed a compound clamp as they are designed to clamp the wire on each side of the blade. One of said clamps being held in closed position independent of the other and both being designed to be closed or clamped at the same time. Rigidly secured to the side of the frame 11 is a slotted casting 87 provided with jaws 88 and is so positioned that the blade 86 is designed to travel in its upward and downward movement in said slot. Mounted on the blade 86 is a jaw 89 designed to engage the jaw 88. The jaw 89 is provided at its lower end with an inwardly extending portion 90 which is provided with a suitable opening through which is inserted a rod 91 which rod extends through a suitable opening in the blade 86 at its upper end and is provided at its lower end with a coil spring 92 and a suitable nut or rivet for holding said spring in place by means of which said jaw is connected to the blade 86. The portion 90 is provided with an arm 93 upon which is adapted to rest a slotted jaw 94 as best shown in Figs. 14 and 14^a. The said jaw 94 is slidably mounted on the casting 87 by means of the slot and pins as shown in Fig. 14^a. One of said pins is provided with a cap 95 for holding said jaw against outward movement while the pin 96 which is rigidly secured to the casting 87 holds said jaw in its upright position. The jaw 94 is provided at its lower edge with an inwardly extending portion designed to be engaged by the arm 93 for forcing said jaw upwardly and clamping the wire in place. Rigidly secured to the lower inward extending portion of the jaw 94 is a suitable rod which extends downwardly through a suitable opening in the arm 93 and is provided with a coil spring and a suitable nut or rivet at its lower end for holding said spring in place as best shown in Fig. 14^a. As the inner end of the blade 86 is moved upwardly by means of the downwardly movement of the link 85 as heretofore described the jaws 87 and 94 are carried upwardly, thus clamping the wire between said jaws and the jaws 88 on either side of the blade as it is cut. It is necessary that the end of the wire is held between the jaws 89 and 88 until the end of the needle strikes the wire and forms a loop

130

(as best shown in Fig. 15) for carrying the wire across to the opposite side. By providing the spring 92 it allows the wire to be forced out of the jaws by means of the 5 needle but holds it sufficiently tight that a loop is formed before it is forced out. The jaws 89 and 88 are held in a closed position until the bar 52 has traveled inwardly sufficiently for the inner end of said bar to engage 10 the arm 62 on the dog 61^a thus releasing the dog 61 from the bell crank lever 55^a at which time the jaws 89 are moved downwardly through the connection described by means of the spring 52^a (Fig. 4) 15 and at the same time the clamps 58 are closed by the same means but through a connection presently to be described.

It is necessary that the bifurcated arm 54 be disengaged from the bar 52 after said 20 bar has traveled inwardly a short distance. This I accomplish by means of the dog 53 which dog is provided with a curved arm 53^b which arm travels in the path of the pin 56^a which engages the curved arm 53^b 25 and forces it out of engagement with the pin 53^a on the arm 54. When the bar 52 has returned to its normal position the spring 53^c returns the dog 53 to its normal position, in which position it is adapted 30 to again engage the pin 53^a on the bar 54.

It is necessary that the end of the wire held between the jaws 94 and 88 should be held in a clamped position until the needles 37 have carried the wire from the opposite 35 side of the baling chamber to the twister. This I accomplish by means of a dog 97 which is pivotally mounted on a suitable support secured to the side of the frame 11 and is designed to engage a suitable notch 40 in the jaw 94 for holding it in a closed position, in which position said jaw will be held until the twisting operation is commenced when it will be released by means of the beveled lug on the periphery of the 45 wheel 66, which lug is designed to engage an arm on the dog 97 and forces it out of engagement with the notch in the jaw 94. After the dog has been released from the jaw 94 the said jaw is returned to its normal 50 or open position by means of the spring shown.

The clamps 58 on the opposite side of the baling chamber which have been heretofore referred to are two in number mounted one 55 above the other directly in the path of the needles 38. As the construction and operation of both of these are the same a description of one will be sufficient for both.

Rigidly secured to the side of the frame 60 11 is a casting 98 which is provided at its upper end with a U shaped inwardly extending portion having bearing surfaces 99. Slidably mounted on said casting by a means presently to be described is a casting 100 65 which is provided at its upper end with an

inverted U shaped portion similar to that in the casting 98 and having bearing surfaces 101 which are designed to engage the bearing surfaces 99. Fulcrumed in the side of the frame 11 is a lever 57^a which is pivotally connected at its inner end by any suitable means to the casting 100 and at its outer end to the link 57 by means of which the casting 100 is given a sliding motion with respect to the casting 98 and by means of which the bearing surfaces 101 are forced upwardly 70 against the bearing surfaces 99 for clamping the wire in place. At the time the end of the needles 38 reach the clamps 58 the end of the bar 52 reaches the arm 62 on the dog 61 thus disengaging the said dog from the pin 63 at which time the bell crank lever 55 is forced outwardly thus forcing the link 57 downwardly and closing the clamps by means of the spring 52^a which spring is 80 best shown in Fig. 4. By providing the U shaped clamps 58 it permits the needles to be driven in and the wire clamped without 85 clamping the needles.

After the free end of the binding wires 90 have been drawn across the baling chamber by the needles 37 it is necessary that these ends be twisted together with the ends cut from the wire leading from the spool by the means above described. I will now describe 95 the means and mechanism for twisting these ends together.

Mounted on the side of the frame 11 opposite from the side on which the clamps 58 are mounted are two twisters which are 100 mounted in a level with the path taken by the wire and directly in the path taken by the needles 37. As the construction and operation of both of these twisters are the same, a description of one will be sufficient 105 for both.

Secured to the frame 11 in any suitable manner is a casing 65 in which is rotatably mounted a hollow cylindrical wheel 66 which is provided on its periphery with an annular 110 groove for mounting the same in the casing 65. The wheel 66 is provided with a stub shaft 67 which extends outwardly through a bracket 68 on which is securely mounted a gear wheel 69. Mounted in the wheel 66 are 115 a pair of pivoted jaws 70 which are provided with diverging arms which diverging arms 71 extend outwardly through slotted openings in the stub shaft 67. Slidably mounted on the stub shaft 67 is a beveled collar 72 120 by means of which said jaws are opened and closed. For actuating said collar I provide a bell crank lever 73 which is pivotally connected at one end by means of a short link to the collar 72 and at its opposite end to a 125 rod 74 which rod is provided with lugs 75 and 76 as best shown in Figs. 1, 5, 6 and 7. The jaws as shown in Fig. 6 are in a closed position and show the wires still being held after the twisting operation is completed 130

and when the jaws are in this position the bell crank 73 would of course be in the position shown in heavy lines in Fig. 6. When the jaws 70 are open they will be in the position shown by dotted lines as will also the bell crank 73. At the time the needles 37 reach the jaws of the twister with the end of the wire to be twisted it is necessary to provide means for closing the jaws. For accomplishing this I provide a rack 77 which is rigidly secured at one end to the side of the auxiliary frame 15 and extends backwardly past the main frame 11 and is provided near its rearward end with a series of gear teeth. Near its forward end is securely mounted a lug 78 which is designed to engage the lug 76 on the rod 74 by means of which the collar 72 is slid outwardly on the shaft 67, thus opening the jaws 70 and releasing the twisted ends of the wire. During the time the lug 78 travels from the lug 76 to the lug 75 the twisting operation is performed by the means now to be described. Rotatably mounted on the bracket 68 is a gear wheel 79 designed to mesh with the gear wheel 69. The gear wheel 79 is provided with the usual pawl and ratchet mechanism as best shown in Fig. 8. The small gear wheel 80 is designed to be engaged by the gear teeth on the rack 77 as above described, both in its outward and rearward travel but by means of the pawl and ratchet device the large gear wheel 79 which meshes with the gear wheel 69 is only rotated during the backward travel of the rack 77 by means of which the jaws are rotated and the ends of the wires twisted. The mechanism is so timed that this twisting operation takes place while the lug 78 travels from the lug 76 to the lug 75 as before stated. It will be understood that the rack 77 is forced backwardly by means of the springs 17 which springs are attached to the auxiliary frame 15 and the main frame as before stated. The jaws 70 are U shaped on the inside, so that the needles may be released and the wire retained as best shown in Fig. 17. It will be understood that the jaws 70 are positioned so that the wire coming from the spool and going around the bale passes between the jaws.

The head block 19 is provided with suitable transverse grooves as best shown in Fig. 9 in which grooves the needles 37 and 38 travel in crossing the baling chamber and by means of which grooves the hay or other material is kept from engaging the needles thus giving a clear and unobstructed path to the needles.

It will be understood that the auxiliary frame 15 may be provided with means for automatically connecting and disconnecting said frame with the plunger rod as will be done on some of the machines in actual practice, instead of the plunger proper as shown

herein, and therefore I do not wish to limit myself to the specific connecting means shown.

It will be seen from the foregoing description that by means of the longitudinal and vertical movement to which the main frame 11 is adapted that the head block is always held in proper alignment with said frame for allowing the needles to be driven across through the grooves in said head block.

To limit the backward movement of the auxiliary frame 15 I provide stops 103 which are rigidly secured to the baling chamber on its upper and lower sides as best shown in Figs. 2 and 4.

While I have herein shown and described only one embodiment of my invention it is to be understood that various changes and modifications may be made by those skilled in the art, without departing from the scope of my invention, as defined in the appended claims.

Having thus described my invention what I claim as new and desire to secure by Letters Patent of the United States is:

1. In a device of the class described, a baling chamber, a pair of binding needles and a pair of threading needles adapted to cross said baling chamber simultaneously from opposite sides, and means for driving said needles across said baling chamber.

2. In a device of the class described, a baling chamber, a frame mounted on said chamber, a pair of binding needles and a pair of threading needles mounted on said frame and adapted to cross said baling chamber simultaneously from opposite sides, and means for driving said needles across said baling chamber.

3. The combination of a baling press, a baling chamber, a main frame mounted on said baling chamber, needles mounted at the side of said baling chamber, a reciprocating plunger in said baling chamber, a head block provided with pins designed to travel in said baling chamber, means mounted on said main frame and adapted to be engaged by the pins on said head block by means of which said main frame is moved longitudinally of the baling chamber a short distance, means adapted to connect with said plunger when said frame has been moved for driving said needles across said baling chamber, and means for actuating said plunger.

4. The combination of a baling press, a baling chamber, a main frame mounted on said baling chamber, needles mounted at the side of said baling chamber, a reciprocating plunger in said baling chamber, a head block provided with pins designed to travel in said baling chamber, means mounted on said main frame and adapted to be engaged by the pins on said head block by means of

which said main frame is moved longitudinally of the baling chamber a short distance, means adapted to connect with said plunger when said frame has been moved for driving said needles across said baling chamber, a 5 twister mounted in said frame, means for operating said twister, and means for automatically returning said needles to their normal position and for operating said twister.

10 5. The combination of a baling press provided with a baling chamber, a reciprocatory plunger in said baling chamber, a main frame mounted on said baling chamber, a threading needle mounted at one side of said baling chamber for carrying a wire across said baling chamber, a binding needle 15 for carrying a binding wire across said baling chamber mounted on the opposite side of said baling chamber, and means connecting with said needles and adapted to connect with said plunger for driving said needles across said baling chamber.

20 6. The combination of a baling press provided with a baling chamber, a main frame mounted on said baling chamber and provided with a telescoping frame, a threading needle for carrying a wire across said baling chamber mounted at one side of said baling chamber, a needle for carrying a binding wire across said baling chamber mounted on the opposite side of said baling chamber, and means for drawing said telescoping frame outwardly whereby said 30 needles are simultaneously driven across said baling chamber.

35 7. The combination of a baling press provided with a baling chamber, a threading needle for carrying a wire across said baling chamber, a needle for carrying a binding wire across said frame said needles designed to cross said chamber simultaneously and from opposite sides and means actuated by the plunger for operating said needles.

40 8. The combination of a baling press provided with a baling chamber, a frame mounted on said chamber, a threading needle for carrying a wire across the front of each bale, a needle for carrying a wire across the rear of each bale, means connecting said needles to said frame whereby said needles are driven simultaneously across said baling chamber and means actuated by the plunger for operating said needles.

45 9. The combination of a baling press provided with a baling chamber, a threading needle for carrying a wire across the front of each bale, a needle for carrying a wire across the rear of each bale, means mounted on said baling chamber for connecting said needles whereby said needles are driven simultaneously across said baling chamber from opposite sides, and means actuated by the plunger for operating said needles.

50 10. The combination of a baling press pro-

vided with a baling chamber, a main frame provided with a telescoping frame mounted on said baling chamber said main frame being adapted to a longitudinal and vertical movement with respect to the said baling chamber, a reciprocatory plunger in said baling chamber, an auxiliary frame connecting to said main frame by means of said telescoping frame, a head block provided with pins designed to travel in said baling chamber, dogs pivotally mounted on said main frame designed to be engaged by the pins on said head block by means of which said main frame is forced longitudinally of the baling chamber a short distance, needles mounted on said frame, a plunger in said baling chamber and means actuated by said plunger for operating said needles and means for actuating said plunger.

55 11. In a device of the class described, a baling chamber, a binding and tying mechanism mounted on said baling chamber, dogs pivotally mounted on said mechanism, a head block provided with pins designed to travel in said baling chamber, said pins being adapted to engage said dogs for starting said mechanism in operation and means mounted on said baling chamber for operating said binding and tying mechanism.

60 12. In a device of the class described, a baling chamber, a telescoping frame mounted on said chamber, needles mounted at the sides of said baling chamber, a reciprocatory plunger in said baling chamber, means for actuating said plunger, and detachable means for connecting said telescoping frame with said plunger whereby said needles are driven across said baling chamber during the outward stroke of said plunger.

65 13. The combination of a baling press provided with a baling chamber, a frame mounted on said chamber, a reciprocatory plunger in said baling chamber, a threading and binding needle mounted on said frame and adapted to carry a wire across said baling chamber from opposite sides, a twister mounted on said frame and adapted to clamp the wire from said binding needle, said twister being adapted to twist the end that is carried across with the opposite end of the wire after the needle has been withdrawn from said twister, a clamp mounted on the opposite side of said frame and adapted to clamp and hold a wire from the threading needle, means for connecting said frame with said plunger for driving said needles across said baling chamber and operating said clamp and means mounted on said baling chamber for returning said needles to their normal position operating said twister.

70 14. The combination of a baling press provided with a baling chamber, a frame mounted on said chamber, a reciprocatory plunger in said baling chamber, a twister mounted on said frame, said twister com-

- prising U shaped jaws mounted within a cylindrical wheel, said wheel being provided with a stub shaft on which is slidably mounted a collar for opening and closing said jaws, means connecting said stub shaft for operating said twister, a binding needle mounted on said frame, means for connecting said frame to said plunger for driving said needle across said baling chamber into said twister and closing said jaws for clamping the wire away from said needle and means mounted on said baling chamber for returning said needle to its normal position and operating said twister.
15. The combination of a baling press provided with a baling chamber, a frame mounted on said chamber, a reciprocatory plunger in said baling chamber, a twister mounted on said frame, said twister comprising U shaped jaws mounted within a cylindrical wheel, said wheel being provided with a stub shaft on which is slidably mounted a collar for opening and closing said jaws, means connecting said stub shaft for operating said twister, a binding needle mounted on said frame, means for connecting said frame to said plunger for driving said needle across said baling chamber into said twister and closing said jaws for clamping the wire away from said needle, means mounted on said baling chamber for returning said needle to its normal position and operating said twister, and means for opening said jaws after the wire has been twisted.
20. The combination of a baling press provided with a baling chamber, a threading needle, a binding needle, and means for driving said needles across said baling chamber substantially at right angles from opposite sides, for the purpose set forth.
25. In a device of the class described, a baling chamber, a frame adapted to longitudinal and vertical movement mounted on said baling chamber, a wire tying, binding, and feeding mechanism mounted on said frame, and means for actuating said mechanism.
30. In a device of the class described, a baling chamber, a frame adapted to longitudinal and vertical movement mounted on said baling chamber, a wire tying, binding, and feeding mechanism mounted on said frame, a reciprocatory plunger in said baling chamber, means on said frame for actuating said binding, tying and feeding mechanism during the outward and rearward stroke of said plunger, detachable means for connecting said frame to said plunger, and means for actuating said plunger.
35. In a device of the class described, a baling chamber, a head block for said baling chamber, a pair of needles designed to cross said baling chamber simultaneously on both sides of said head block.
40. In a device of the class described, a baling chamber, a reciprocatory plunger therein, a main frame mounted on said chamber having an auxiliary telescoping frame attached thereto, a wire tying mechanism mounted on said main frame, a rack carried by said auxiliary frame and designed to operatively engage said tying mechanism during its rearward travel, and means for throwing said tying mechanism out of operation during the outward travel of said rack.
45. In a device of the class described, a baling chamber, a reciprocatory plunger therein, a main frame mounted on said chamber having an auxiliary telescoping frame attached thereto, needles mounted at the side of said baling chamber, means connecting said auxiliary frame with said plunger during the outward travel of said plunger whereby said needles are driven across said baling chamber, and means for actuating said plunger.
50. In a device of the class described, a baling chamber, a reciprocatory plunger therein, a main frame mounted on said chamber having an auxiliary telescoping frame attached thereto, needles mounted at the side of said baling chamber, means connecting said auxiliary frame with said plunger during the outward travel of said plunger whereby said needles are driven across said baling chamber, means for automatically disconnecting said auxiliary frame from said plunger before said plunger has reached its outward limit of movement, a tying mechanism mounted on said main frame, a rack carried by said auxiliary frame and designed to operatively engage said tying mechanism during its rearward travel, means for returning said auxiliary frame, and means for actuating said plunger.
55. In a device of the class described, a baling chamber, a reciprocatory plunger therein, a main frame mounted on said chamber having an auxiliary telescoping frame attached thereto, needles mounted at the side of said baling chamber, means connecting said auxiliary frame with said plunger during the outward travel of said plunger whereby said needles are driven across said baling chamber, a cutting mechanism mounted on said main frame and adapted to cut the baling wire as said needles start across said baling chamber, a tying mechanism mounted on said main frame, a rack carried by said auxiliary frame for operating said tying mechanism during its rearward travel, a clamp mechanism mounted on said main frame and adapted to securely hold the baling wire, going around the bale until the tying mechanism commences operation, means for automatically disengaging said clamp when said tying mechanism commences operation, means for automatically disengaging said auxiliary frame from said

plunger before said plunger has reached its outward limit of movement, means for returning said auxiliary frame, and means for actuating said plunger.

- 5 24. In a device of the class described, a baling chamber, a reciprocatory plunger therein, a main frame mounted on said baling chamber having a telescoping auxiliary frame attached thereto, a tying mechanism 10 mounted on said main frame, a rack carried by said auxiliary frame and adapted to operatively engage said tying mechanism during its rearward travel, and means for operating said auxiliary frame.
- 15 25. In a device of the class described, a baling chamber, a reciprocatory plunger therein, a main frame mounted on said baling chamber having a telescoping auxiliary frame attached thereto, means for operatively connecting and disconnecting said auxiliary frame to and from said plunger, a clamp mechanism mounted on said main frame, means for closing said clamp as said auxiliary frame starts on its outward travel, 20 25 a tying mechanism mounted on said main frame, a rack carried by said auxiliary frame for operating said tying mechanism during its inward travel, means for holding said clamp in its closed position until said 30 35 tying mechanism begins operation, means on said tying mechanism for automatically releasing said clamp, means for returning said auxiliary frame, and means for actuating said plunger.
- 35 26. In a device of the class described, a baling chamber, a reciprocatory plunger therein, a main frame mounted on said baling chamber, a double telescoping auxiliary frame operatively attached thereto, needles 40 45 mounted at the side of said baling chamber and adapted to be driven across said baling chamber, means for operatively connecting and disconnecting said auxiliary frame with said plunger whereby said needles are driven across said baling chamber, means for returning said auxiliary frame whereby said needles are returned to their normal position, and means for actuating said plunger.
- 50 27. In a device of the class described, a baling chamber, a reciprocatory plunger therein, head blocks spaced apart and designed to travel through said baling chamber, means for throwing slack in the binding wire mounted on said main frame and de- 55 signed to be operated by one of said head blocks as said head block is moved through

the baling chamber, and means for moving said head block through the baling chamber.

28. In a device of the class described, a baling chamber, a reciprocatory plunger 60 therein, head blocks spaced apart and designed to travel through said baling chamber, a main frame mounted on said baling chamber, means mounted on said main frame and designed to be operated by said head 65 blocks as they travel through said baling chamber for throwing slack in the binding wire, and means for forcing said head blocks through said baling chamber for the purpose set forth.

70

29. In a device of the class described, a baling chamber, a reciprocatory plunger therein, a main frame mounted on said baling chamber, a telescoping auxiliary frame mounted on said main frame, a pair of 75 needles on either side of said baling chamber, a head block for said baling chamber, means for driving said needles across said baling chamber on either side of said head block, means for returning said needles to 80 their normal position, and means for holding said head block in its relative position until said needles are returned to their normal position.

85

30. In a device of the class described, a 85 wire tying mechanism, comprising a pair of grooved jaws having oppositely and rearwardly extending arms formed integrally therewith and pivotally mounted in a rotatable shaft, a collar slidably mounted on 90 said shaft, means for sliding said collar on said shaft for opening and closing said jaws, and means for rotating said shaft.

31. In a device of the class described, a baling chamber, a reciprocatory plunger 95 therein, a frame mounted on said baling chamber, a needle on either side of said baling chamber, a head block for said baling chamber, means for driving said needles across said baling chamber on either side of 100 said head block, means for returning said needles to their normal position, and means for holding said head block in its relative position until said needles are returned to their normal position.

105

In witness whereof, I hereunto subscribe my name this 20th day of August A. D. 1912.

JAMES LEONARD LAMB.
